TWO-TEMPERATURE REFRIGERATOR HAVING SPECIAL AIR DIRECTING BAFFLE

John M. Murphy, Oakwood, Ohio, assignor to
General Motors Corporation, Dayton, Ohio, a
corporation of Delaware

Application March 4, 1952, Serial No. 274,691

2 Claims. (Cl. 62—103)

1

This invention relates to refrigerating apparatus and more particularly to an improved arrangement of elements within the food storage compartment of a household refrigerator.

It has been found that it is now possible to connect two evaporators in series with a refrigerant liquefying unit and to use the one evaporator for producing below freezing temperatures in a frozen food compartment and to use the other evaporator for maintaining above freezing temperatures in the main food storage compartment. It has also been found possible to defrost the one evaporator located in the relatively high temperature compartment during each off cycle without thawing any of the frozen foods in the other compartment. In a system of this type, it has been found preferable to mount the defrosting evaporator adjacent the upper rear wall of the main food storage compartment and to arrange the frozen food compartment in the upper part of the cabinet. The ceiling of the main food storage compartment then is formed by the bottom of the frozen food compartment and remains fairly cold even during the peak of the defrost portion of the cycle at which time the humidity in the compartment is at its highest with the result that moisture tends to condense on this surface. It is an object of this invention to provide a multiple purpose air directing baffle which not only prevents dripping of this condensate onto the food but which also improves the air flow over the defrosting evaporator so as to facilitate defrosting.

Another object of this invention is to provide an improved condensate drain arrangement.

Further objects and advantages of the present invention will be apparent from the following description, reference being had to the accompanying drawings, wherein a preferred form of the present invention is clearly shown.

In the drawings:

Figure 1 is a vertical sectional view partly schematic showing the arrangement of elements within the main food storage compartment of a household refrigerator embodying the invention; and

Figure 2 is a fragmentary front elevational view showing the construction and location of the air directing baffle within the food storage compartment.

Referring now to the drawings for a more detailed description of the invention, the reference numeral 10 designates an insulated refrigerator cabinet having an inner liner 12 forming a food storage compartment 14 which is insulated from a machinery compartment 16 located in the lower portion of the cabinet 10 in accordance with con-

ventional practice. A conventional access door 18 is provided for the compartment 14 as shown. An insulated frozen food storage chamber 20, having an access door 22, is mounted within the upper portion of the cabinet 10 so that the bottom of the chamber 20 forms the ceiling of the main food compartment 14. Since the construction of the cabinet 10 and the frozen food chamber 20 may be varied without departing from the spirit of my invention, and since structures of this type are well known to those skilled in the art they will not be described in greater detail. For a more complete description of the same, reference is hereby made to co-pending application Serial Number 223,590, filed in the United States Patent Office on April 28, 1951.

The frozen food storage chamber 20 and the main food storage compartment 14 are refrigerated by means of a pair of evaporators 24 and 26 which are connected in series refrigerant flow relationship with the refrigerant liquefying apparatus located within the machinery compartment 16. Thus, a conventional motor-compressor unit 28 withdraws the vaporized refrigerant from the plate type evaporator 26 which is located adjacent the upper rear portion of the food storage compartment 14 and discharges the compressed refrigerant into a conventional condenser 30 from whence liquid refrigerant flows into the evaporator 24 through a capillary tube of restrictor 32. The outlet of the evaporator 24 is connected to the inlet of the evaporator 26 by means of a line 34. A switch 33 controlled by a thermostat 35 located on the lower corner of the evaporator 26 cycles the compressor and functions to stop the compressor when the temperature of the thermostat falls below -2° F. and restarts the compressor when the temperature of the thermostat reaches 36° F. The construction and arrangement of the evaporators and the insulation for the compartments is such that freezing temperatures are maintained within the chamber 20 at all times whereas the plate type evaporator 26 which is located in the relatively warm food storage compartment 14 will defrost during the off portion of each cycle.

Since the temperatures within the frozen food storage chamber 20 are maintained considerably below freezing there is a tendency for condensate to collect on the bottom wall 36 of the freezer compartment 20 and the outer surface of the inner door 22. Unless some means is provided for collecting this condensate it will tend to drip onto the food stored within the compartment 14. It is not practical to provide a pan for this purpose as the pan would require emptying from time to time.

In the refrigerator shown, a baffle 40 has been provided which has a forwardly extending lip 42 which collects condensate from the door 22 and which has a horizontally extending portion underlying the frozen food chamber 20 for collecting any condensate which may drip from the bottom wall 36. The baffle slopes towards the rear whereby condensate flows to the rear edge of the baffle 40 and is then discharged at a point directly over the plate type evaporator 26. A condensate collecting trough 44 is provided directly beneath the evaporator 26 for collecting the condensate and any defrost water draining off from the evaporator 26. The condensate collecting trough 44 does not hold the condensate but merely directs it onto the rear wall of the liner 12 as shown in Figure 1, so that the condensate will flow down along the rear wall and moisten this wall. Any suitable means may be provided for directing the water into contact with the rear wall. For purposes of illustration the wall is shown with a rib 46 directly beneath the trough 44. Some of the condensate flowing down the wall will reevaporate into the air so as to maintain a humid atmosphere in the food compartment 14. The overflow or excess condensate will run into a bottom drain 50 provided as shown for discharging the condensate into a removable condensate collecting tray 52 located in the machinery compartment 16. The heat of the machinery compartment 16 will tend to vaporize the condensate therein with the result that under ordinary atmospheric conditions it will never be necessary to empty the pan 52. The usual vegetable storage means 53 may be provided adjacent the bottom of the food compartment 14.

The problem of defrosting the evaporator 26 during the off cycle of the refrigerator presents a problem as it is important to have the very light coating of ice which forms on the evaporator 26 to melt promptly during the off cycle, before the entire contents of the food storage compartment 12 warm up excessively. It has been found that the warmest air in the compartments tends to collect in the upper part of the food storage compartment 14 and it is this air which would be the most effective in defrosting the evaporator 26 and it is this air which would most benefit by giving up heat to the ice on the evaporator so as to defrost the same. It has been discovered that by arranging the evaporator 26 and the baffle 40 as shown improved air circulation takes place which facilitates the defrosting operation of the evaporator section 26.

Thus, it is seen that the baffle 40 not only serves to prevent dripping of water onto the food, but also serves an important function of facilitating the circulation of warm air over the evaporator and between the evaporator 26 and the rear wall of the liner 12 so as to facilitate defrosting the rear side of the evaporator 26.

The baffle 40 serves another useful function in that it is provided with guides 54 for a special food drawer 56 which is slidably relative to the baffle 40. This food drawer 56, being arranged in the warmest portion of the food storage compartment, serves as a convenient place for storing cheese, butter and other similar items.

The baffle 40 is preferably made of plastic and is adapted to be supported at its sides by supports 58 (see Figure 2) provided on the side walls of the liner 12. The rear center edge of the pan is supported by means of a spring clip 60 which engages a projection 62 formed on the baffle 40. The front central portion is further

supported by means of a spring latch element 64 carried by the lower wall of the frozen food chamber 20. This spring latch 64 engages a latch engaging element 66 secured to the central front portion of the baffle 40. By virtue of the above described construction it is possible to make the baffle out of light weight plastic material.

While the form of embodiment of the invention as herein disclosed constitutes a preferred form, it is to be understood that other forms might be adopted, as may come within the scope of the claims which follow.

What is claimed is as follows:

1. In a refrigerator having a food storage compartment and a frozen food compartment, a first evaporator for cooling said frozen food compartment, a second evaporator for cooling said food storage compartment, said frozen food compartment being disposed above said food storage compartment, an outer door for providing access to said compartments, an inner door for said frozen food compartment, said second evaporator comprising a plate type evaporator disposed horizontally adjacent the upper rear portion of said food storage compartment, an air directing baffle supported beneath said frozen food compartment so as to intercept condensate formed on the lower surface of said frozen food compartment and to convey said condensate to a point substantially above said plate type evaporator, means for directing the condensate leaving said plate type evaporator onto the rear wall of said food storage compartment, a food drawer, and means for slidably supporting said food drawer adjacent the bottom surface of said baffle whereby said baffle serves to close the upper side of said drawer.

2. In a refrigerator having a food storage compartment and a frozen food compartment, a first evaporator for cooling said frozen food compartment, a second evaporator for cooling said food storage compartment, said frozen food compartment being disposed above said food storage compartment, an outer door for providing access to said compartments, an inner door for said frozen food compartment, said second evaporator comprising a plate type evaporator disposed in a vertical plane adjacent the upper rear portion of said food storage compartment, a plastic baffle, means for removably supporting said baffle beneath said frozen food compartment so as to intercept condensate formed on the lower surface of said frozen food compartment and to convey said condensate to a point substantially above said plate type evaporator, and means for directing the condensate leaving said plate type evaporator onto one wall of said food storage compartment, said means for removably supporting said baffle including means for engaging both sides and the front and back central portions thereof.

JOHN M. MURPHY.
